UNITED STATES PATENT OFFICE.

WILLIAM G. COUGHLIN, OF PHILADELPHIA, PENNSYLVANIA.

RAIL-FASTENING.

1,316,941.

Specification of Letters Patent. Patented Sept. 23, 1919.

Application filed March 1, 1919. Serial No. 280,015.

To all whom it may concern:

Be it known that I, WILLIAM G. COUGHLIN, a citizen of the United States, and residing at Philadelphia, Philadelphia county, State 5 of Pennsylvania, have invented certain new and useful Improvements in Rail-Fastenings, of which the following is a specification.

This invention relates to rail fastenings 10 for railroads, particularly to adjustable fastenings of this character and its objects are to provide such a device which may be used with all forms of rail support, and with nearly all kinds of rails, and which at the 15 same time allows "gaging", "lining" and "surfacing" of the trackway without removing the device from the support.

The invention will be fully disclosed in the following description when taken in 20 connection with the accompanying drawings, in which—

Figure 1 is a top view of a wooden tie supporting T rails and having my improved rail fastening incorporated therewith;

25 Fig. 2 is a side view of the same;

Fig. 3 is an end view;

Fig. 4 is a top view of a concrete tie supporting T rails and having my improved fastening devices;

30 Fig. 5 is a side view of the same;

Fig. 6 is an end view of the tie shown in Figs. 4 and 5;

Fig. 7 is a plan view of a section of concrete roadbed showing my improved rail 35 fastening used therewith to secure T rails;

Fig. 8 is a sectional view of the roadbed;

Fig. 9 is a side view of a portion of the same;

40 Fig. 10 is an enlarged side view of the rail fastening;

Fig. 11 is a view of the same from the inside of the rail;

Fig. 12 is a view of the same from the outside of the rail; and

45 Fig. 13 is a view of a detail.

The improved rail fastening may be used with almost any form of rail and with any form of rail support and in the drawings I have shown it in connection with wooden ties, concrete ties and a solid concrete support, but for convenience will describe it in detail when used in connection with only one of these forms of support, which is the roadbed disclosed in Figs. 7, 8, 9, 10, 11 and

12. In this form of support a heavy concrete base 10 is provided through which run reinforcing bars 11 in any desired manner to give the same great strength and rigidity. In addition to the necessary reinforcing bars 11, additional transverse bars 60 12 extend through the concrete mass near its upper surface.

These anchor bars 12 have U-shaped portions or offsets 13 and 14 near their outer ends, so spaced relatively that the bars 12 cross and recross the recesses 15 in the concrete base, on opposite sides of each rail of the track, the exposed portions being substantially parallel to the rails. The transverse bars 12 will hereinafter be known as anchor 70 bars, as the portions of the same which are exposed due to its crossing and recrossing the recesses 15, serve as anchor points to which the rail securing means now to be described is anchored.

Referring particularly to Figs. 10, 11 and 12 it is seen that the T rail 16 having the usual flanged base is supported upon a wooden shim 17, which is tapered and which rests upon the inclined upper surface of the 80 base, the taper of the shim being such that its upper surface is substantially horizontal, or inclined downwardly toward the center of the trackway thus tipping the rail slightly inward, if this is desired. The rails 16 are 85 entirely supported by these wooden shims 17 which are arranged at about the same intervals as wooden ties in the ordinary roadbed. Because of the wedge shape of the shim, the rail can be raised or lowered by moving the 90 shim toward or from the center of the trackway. This is a very desirable feature as it enables the rails to be leveled properly or given their correct relative elevations, which is called "surfacing".

Angle irons 18 abut against the outer ends of the shim 17, each of these angle irons being provided with a short screw bolt 19, which passes through an opening in the horizontal part of the angle iron and the lower 100 end of which is adapted to enter any one of a series of holes 20 in the metallic strip 21 inlaid in the concrete. The angle iron prevents the shim from moving longitudinally out of place accidentally, while at the 105 same time does not hinder its ready adjustment when desired. The elongated recesses 15 in the concrete base alternate with the

wooden shims and there is located at each of these recesses a rail fastening for adjustably securing the rail to the support.

Engaging the base or bottom flange of the rail at each of the points where it is secured are two clips 22 and 23 arranged on opposite sides thereof, each of which is secured to the anchor bar on the opposite side of the rail by a bolt, the inner clip 23 of the two being secured to both anchor bars. The securing bolts above mentioned are indicated at 24, 25 and 26 in the drawings and all of the bolts are substantially alike although they vary in length. Each is provided at one end with a bent portion or hook and at the other end with a threaded portion of suitable length adapted to receive a threaded nut as indicated at 27. The bolts pass through tapered openings in the clips 22 and 23, one of such openings being provided in the outer clip 22 and two in the inner clip 23, and the openings being tapered in such manner that when the bolts alter their angles with the horizontal due to the raising or lowering of the rail, there will be no interference between the bolts and the walls of the openings.

The nuts 27 do not bear directly on the clips, but upon spring washers 28 having convex lower surfaces which fit into recesses 29 in clips 22 and 23 having correspondingly curved bottoms. These spring washers absorb the shock and strain due to the passing of a train along the trackway and their spherical bases always permit their being seated normally with the line of thrust along the bolt. The lower ends of the securing bolts are hooked over the anchor bars and after the rail is adjusted vertically and horizontally to its correct position, and longitudinally if necessary, the bolt nuts 27 are tightened and the rail is secured in such position until such time when readjustment is thought necessary. If the gage of the track has become faulty, or the rails are not exactly in straight lines, &c., or it needs readjustment for elevation, it is only necessary to loosen the bolts and to manually readjust the rail to its proper position after which they may be tightened and the rail secured to its true position. These various operations are called "gaging", "lining" and "surfacing" and are the common operations constantly performed in maintaining the track way in perfect condition.

It is to be noted that to accomplish these various adjustments it was necessary only to loosen the nuts 27 and that no portion of the device was removed from its position. It is also obvious that one type of rail might be completely removed from the roadbed and another type placed thereon and that the fastening described would permit this to be done without substituting any special parts, except, in some instances, clips of a different

shape. In other words, the fastening is practically a universal one for all types of rails.

In order to prevent the longitudinal creeping of the rail, I have flared the upper jaws of the clips as shown at 30 and 31 in the drawings. If the rail has a tendency to creep, the edges of the flared portions will have a tendency to bite into the inclined upper surface of the flanges and to prevent movement.

By arranging each of the anchor bars at some distance to the side of the rail, the longitudinal axes of the bolts make only small angles with the horizontal and thereby are very nearly parallel with the line of thrust which a passing train exerts on the rail and which tends to overturn it or spread the rails. The maximum strength of the fastening in this respect for a given weight of metal is thereby realized.

An important feature of my invention is that one of the rail securing clips is anchored at two different points in the support. This arrangement absolutely prevents this particular clip from moving vertically or horizontally since it is at one apex of a triangle the length of whose sides can not change. The anchoring of one clip to two different points gives a rigidity to the entire fastening which is not present in fastenings of this character heretofore designed, in which the clips or other rail securing devices have been secured by single bolts only, in which case it is impossible to have absolute security against rotation of the entire securing device about its anchor point or deformation of the system in case two anchoring points are used, one for each clip.

The device is simple, inexpensive, easily adjusted and very easy to install in the first place. After the support has been prepared and the anchor bars located, it is only necessary to place the rails on the wooden shims, adjust them for line, gage, and surface, hook the bolts 24, 25 and 26 over the anchor bars and tighten up the nuts 27 when the fastening will retain the rail until such time as further adjustment is required.

In Figs. 1, 2 and 3 which illustrate wooden ties the anchor bars pass through openings located at or near the horizontal center line of the ties and extend outwardly on each side, the securing bolts being anchored to the ends of the same which protrude from the ties. Clips are placed on each side of the tie so that no unbalanced forces will be placed on the anchor bolts which might tend to turn the tie over and it is obvious that every other tie in the roadbed only need be provided with the rail fastenings.

In Figs. 4, 5 and 6 I have illustrated the improved rail fastening device used in connection with a concrete tie. Its arrangement is exactly the same as in the case of the

wooden tie and it accomplished the same functions, the only difference being in the method of arranging the anchor bars, a number of different ways for doing which may 5 be devised.

- In connection with the fastening above described, suitable tie plates may be used if desired. The fastening may be used to secure switches, frogs or other special rails 10 and as stated previously comprises an inexpensive and convenient fastening device applicable to all types of rail supports and rails, which may be easily adjusted in "gaging", "surfacing" and "lining" the rails and 15 which is absolutely rigid because of its truss-like structure.

Having thus described my invention what I desire to secure by Letters Patent is:

1. A rail fastening comprising, in combination with the rail and support therefor, 20 separated anchor bars secured in the support below the base of the rail, clips engaging the base of the rail on opposite sides thereof, two bolts connecting said clips with said anchor 25 bars respectively and a third bolt connecting one of said clips with one of said anchor bars, for the purpose set forth.

2. A rail fastening comprising, in combination with a rail and a support therefor, 30 two anchor bars secured in the support below the base of the rail one being arranged on each side thereof, clips engaging the base of the rail on opposite sides thereof, two bolts connecting said clips to said anchor bars 35 respectively and a third bolt connecting one of said clips with one of said anchor bars, for the purpose set forth.

3. A rail fastening comprising, in combination with a rail and a support therefor, 40 separated anchor bars secured in the support below the base of the rail, clips engaging the base of the rail on opposite sides thereof, the clip on the inner side of the rail base being provided with two tapering openings there- 45 through and the clip on the outer side of the rail base being provided with a single tapering opening, said openings being adapted to receive bolts passing therethrough, two bolts passing through said openings in the 50 inner clip and connecting the same with two anchor bars, and a third bolt passing through the opening in said outer clip and connecting the same with the inner bar, for the purpose set forth.

- 55 4. A rail fastening comprising, in combination with a rail and a support therefor, separated anchor bars secured in the support below the base of the rail, clips engaging the base of the rail on opposite sides thereof, 60 said clips having openings therethrough for bolts and spherical recesses at the upper

ends of said openings and concentric therewith, two bolts connecting said clips with said anchor bars respectively and a third bolt connecting one of said clips with one 65 of said anchor bars, said bolts having spring washers with spherical bases at their upper ends, the spherical bases of the washers being adapted to seat in the spherical recesses of the clips whereby the washer will be seated 70 normally with the line of thrust of the bolt.

5. A rail fastening comprising, in combination with the rail and support therefor, separated anchor bars connected in the support below the base of the rail, clips engag- 75 ing the base of the rail on opposite sides thereof, two bolts connecting said clips with said anchor bars respectively and a third bolt connecting one of said clips with one of said anchor bars, the lower ends of said 80 bolts being provided with hooked portions extending around said anchor bars allowing them to be readily removed when desired, for the purpose set forth.

6. A rail fastening comprising, in combination with a rail and a tie supporting the same, separated anchor bars secured to said tie at or near its horizontal center line, clips engaging the base of the rail on opposite 85 sides thereof, two bolts connecting said clips 90 with said anchor bars respectively and a third bolt connecting one of said clips with one of said anchor bars, for the purpose set forth.

7. A rail fastening comprising, in combination with a rail, a support therefor and a wedge or tapered shim between said rail and said support for vertically adjusting the rail, separated anchor bars secured in the support below the base of the rail, clips 100 engaging the base of the rail on opposite sides thereof, two bolts connecting said clips with said anchor bars respectively and a third bolt connecting one of said clips with one of said anchor bars, for the purpose set 105 forth.

8. A rail fastening comprising, in combination with a rail, a support therefor, a tapered shim or wedge between the rail and support for adjusting the elevation of the 110 rail and means for securing said wedge or tapered shim in any desired position, of separated anchor bolts secured in the support below the base of the rail, clips engaging the base of the rail on opposite sides thereof, 115 two bolts connecting said clips with anchor bars respectively and a third bolt connecting one of said clips with one of said anchor bars, for the purpose set forth.

In testimony whereof I affix my signature. 120

WILLIAM G. COUGHLIN.
